US0D1092132S

(12) **United States Design Patent** (10) **Patent No.:** **US D1,092,132 S**
(45) **Date of Patent:** **** Sep. 9, 2025**

(54) **PLASTIC LID**

(71) Applicant: **Hunan Haochen Technology Co., Ltd.**,
Changsha (CN)

(72) Inventor: **Shuai Zuo**, Honghu (CN)

(73) Assignee: **Hunan Haochen Technology Co., Ltd.**,
Changsha (CN)

(*) Notice: Patent file contains an affidavit/declaration
under 37 CFR 1.130(b).

(**) Term: **15 Years**

(21) Appl. No.: **29/982,275**

(22) Filed: **Jan. 6, 2025**

(51) LOC (15) Cl. **07-07**

(52) U.S. Cl.

USPC **D7/391**
